UNITED STATES PATENT OFFICE.

BENJAMIN M. HANNA, OF PITTSBURGH, PENNSYLVANIA.

SPECTACLE-GLASS.

1,103,962.

Specification of Letters Patent. Patented July 21, 1914.

Application filed January 29, 1914. Serial No. 815,125.

To all whom it may concern:

Be it known that I, BENJAMIN M. HANNA, residing at Pittsburgh, in the county of Allegheny and State of Pennsylvania, a citizen of the United States, have invented or discovered certain new and useful Improvements in Spectacle-Glasses, of which improvements the following is a specification.

10 My invention relates to improvements in bi-focal eye-glasses, and the object of my improvement is to overcome certain objectionable features which these glasses as they are now constructed possess.

15 The invention is illustrated in the accompanying drawings.

Figures 1 and 2 show in side elevation and in vertical medial section on larger scale a bi-focal eyeglass formed in the manner now generally employed. These two figures are introduced for purposes of comparison with the remaining figures which illustrate my invention. Figs. 3, 6, and 7 show in side elevation and with variation 25 in detail eyeglasses embodying my invention, and Figs. 4 and 5 show the glass in vertical medial section and on larger scale. Three alternate forms in elevation are shown and two alternates in section; and it

30 is to be understood that either of the sectional alternates is applicable to any one of the three elevation alternates. Fig. 8 is a diagrammatic illustration to which a passage in the ensuing description particularly refers. Figs. 9, 10, and 11 are three sectional views corresponding to Fig. 4, but on much 35 larger scale, and illustrating more minute permissible variations in detail. Fig. 12 is a view corresponding to Figs. 3, 6, and 7, 40 and illustrates a further variation in detail of construction.

In bi-focal spectacle glasses, it is desirable to have the largest possible area of the secondary or reading lens, for downward 45 vision, and at the same time to intrude as little as may be upon the area of the primary or distance lens, for level vision. Consequently the secondary or reading lens is ordinarily arranged in the lower portion of 50 the spectacle glass and is in plan of the lenticular shape, shown in Fig. 1 of the ac-

companying drawings—the lower edge *a* conforming to the lower margin of the glass and the upper edge *b* convex.

The method now ordinarily employed in 55 making these spectacle glasses is to apply the lens 2 against the face of the body 1, uniting the parts by cement, ordinarily Canada balsam. This is indicated in Fig. 2 of the drawings (a section on the line II— 60 II, Fig. 1), in which the surfaces of union by cement are indicated by the line *c*. Cement changes in time and service, to the impairment of the optical properties of the glass, and is for that reason undesirable. 65

My invention is directed to avoidance of the necessity of using cement over the surfaces through which vision is gained.

In a co-pending application, filed December 23, 1913, Serial No. 808,497, I have 70 described and claimed a method of uniting bodies of glass while in solid state, and have described it as serviceable in making bi-focal eyeglasses. The method involves an application of the principles of thermal 75 expansion.

My present invention has to do with the shaping of the component parts of bi-focal eyeglasses, and is, in part, disclosed in the application referred to. 80

In the practice of my present invention, I recess the main body of the spectacle glass for the reception of the reading lens; and this recess may extend through the main body (Fig. 5) or may be superficial, upon 85 one face of the main body (Fig. 4); and I secure the reading lens within this recess by an edge-to-edge engagement only, thus avoiding the necessity of using a cement over surfaces through which vision is to 90 be had.

If I were to attempt to form within the main body a recess (whether superficial or extending through) for the inserted reading lens of the shape in plan shown in Fig. 95 1, I would be unable to get security of union by any edge-to-edge engagement known to me. Cement would not, with such a shape, be adequate; the shocks incident to use would soon loosen the reading lens and it 100 would fall out. But when I adopt either of the shapes shown in Figs. 7 and 8 of the ap-

lication referred to (Figs. 3 and 6 of this application), I may then unite the components, either by the differential heat method described in that other application, or by 5 the use of cement or other filling material along the edges only, or by both means, and obtain a union secure for service.

Referring first to Figs. 3 and 6, it will be observed that the upper edge of the secondary lens, instead of being formed of simple 10 divergent curvature, as shown in Fig. 1, is formed with a slight convergence of curvature, which may be at the periphery, as illustrated at α , α , Fig. 3, or at intermediate 15 points, as illustrated at y , y , Fig. 6. In these cases the secondary lens member may be set in a superficial recess prepared for it in the body of the primary lens member, as indicated in Fig. 4, or may occupy the 20 whole thickness of the spectacle glass, as indicated in Fig. 5. As has been intimated, the relative dimensions of the recess and of the secondary lens which is inserted within it may be such that union is effected by the 25 differential temperature method of my pending application hereinabove referred to, and in such case I may or may not use cement or other filling material along the edges; or the relative dimensions may be 30 such as to require the application of such material to the edges. The application of cement or other material may extend all the way around the engaging edges or part way, as desired. The presence of such material 35 at the edge, aside from its value if any as an adhesive, is useful to exclude moisture and dust from between the lens faces. The secondary or reading lens 2 may be inserted in its recess either in a direction transverse 40 to the face of the glass, or (the overhanging points formed by convergent curvature at α and y , Figs. 3 and 6, being of proper size and the relative dimensions permitting) the secondary lens 2 may be inserted in an edge-wise direction, *i. e.* parallel with the general 45 plane of the glass.

My present application in its broadest aspect is not however limited to the shaping of the meeting edges of the lens parts with 50 portions of converging curvature. This will be apparent on consideration of Fig. 7 and the diagrammatic showing of Fig. 8. The dotted lines b of Fig. 8 illustrate the usual contour (see Fig. 1); my improvement lies 55 in breaking this contour line, and forming the contour with the opposing, and in this case parallel, lines z , z . In this case, let it be imagined that a strain is exerted (the jar of a fall, for instance), tending to separate 60 the components, and acting in the direction indicated by the arrow k . In case the contour is as usual (indicated at b) the strain is unopposed, and if sufficiently severe will cause the inserted secondary lens 2 to break

away from the containing body 1; but, in 65 the case of the contour of my invention, the strain is opposed by the bearing along edge z ; and, unless increased very much beyond that sufficient to cause separation in the other case, the union will be secure.

The latitude of permissible variation in detail of structure is further indicated in Fig. 12; the main body and the insert may be keyed together and the particular disposition of the key may be such as is preferred. In Fig. 12 it appears that a recess may be 70 formed in the edges of contact extending into the body 1 on one side and the insert 2 on the other, and into this recess a key 3 may be let, and this key will be effective to 75 hold the component parts of the eyeglass against separation. Stated in other words, and in view of the variations now explained, my invention consists in a certain shaping 80 of the parts; and it will be observed that in each illustration there are surfaces designed to resist and overcome oblique strains tending to separate the component lenses of the 85 spectacle glass. And it will be noted in this connection that the oblique strains thus 90 guarded against are more effective to cause separation (if not guarded against) than vertical strains—*i. e.* parallel with the edges z , z of Fig. 8.

Figs. 9, 10, and 11 are intended to show 95 that the meeting edges of insert and recess may be shaped variously, as indicated at m , n , o . The form shown at o , if made flaring to a marked degree, would not be effective to afford union by the differential 100 temperature method of the application referred to, but would require the application of cement to the meeting edges. The shape indicated in Fig. 9, wherein the insert 105 2 is held in the body 1 against lateral displacement by the overhanging rim of the edge m of the recess is preferred. This overhanging rim will be effective whether engaging the inserted lens directly, or indirectly through a body of cement or other 110 material, to increase the security of such insert. This feature is effective, regardless of the particular position of the insert within the main body of the glass—*i. e.* whether or 115 not it be marginal.

I claim as my invention:

1. In a bi-focal eyeglass, the combination of a primary lens having a marginal recess and a secondary lens inserted in such recess, the edges of such recess being in the main divergent toward the margin but their divergence being interrupted and the interruption affording surfaces opposed to oblique strains tending to separation of the secondary lens when in place in the said recess of the primary lens.

2. A bi-focal eyeglass in which the normal curve of the edge of union of containing

body and insert is broken by an irregularity affording surfaces opposed to oblique strains tending to separation.

3. In a bi-focal eyeglass, the combination of a primary lens, and a secondary lens carried in a recess in the primary lens, the edge of the recess in the primary lens being formed with an overhanging rim.

4. In a bi-focal eyeglass, the combination of a primary lens having a marginal recess

and a secondary lens inserted in such recess, the edges of such recess being interrupted by overhanging points.

In testimony whereof I have hereunto set my hand.

BENJAMIN M. HANNA.
